(57) **ABSTRACT**

A humidifier is provided that includes a main body having a discharge part, a base on which the main body is seated, the base having a suction part through which air is suctioned, a tray seated on the base to store water, and a disk assembly seated on the tray to humidify the air suctioned through the suction part.

HUMIDIFIER

**CROSS-REFERENCE TO RELATED
APPLICATION**

The present application claims priority under 35 U.S.C. 119 and 35 U.S.C. 365 to Korean Patent Application No. 10-2013-0127094, filed Oct. 24, 2013, the subject matter of which is hereby incorporated by reference.

BACKGROUND

Humidifiers are devices for discharging moisture contained in air to raise humidity in the air. Humidifiers may be classified as ultrasonic humidifiers using ultrasonic vibration and natural vaporizing humidifiers in which flowing air contacts moisture to allow the air to contain the moisture.

Korean Patent Publication No. 2012-0136137, the subject matter of which is incorporated herein by reference, discloses a humidification air cleaner.

The humidification air cleaner has an inflow hole for introducing air in a plurality of portions of a side surface of an upper case and an air discharge part for discharging air in a top surface of the upper case.

However, according to the above-described humidification air cleaner, since the plurality of inflow holes are defined in the side surface of the upper case, the inflow holes may be exposed to deteriorate a sensor of beauty. Additionally, foreign substances may be introduced through the inflow holes, or the inside of the upper case may be exposed.

Additionally, since the foreign substances passing through the inflow holes directly drop down into a lower case to contaminate water, humidification may be performed by using the contaminated water to deteriorate cleanliness.

BRIEF DESCRIPTION OF THE DRAWINGS

Arrangements and embodiments may be described in detail with reference to the following drawings in which like reference numerals refer to like elements and wherein:

FIG. 1 is a perspective view of a humidifier according to an example embodiment;

FIG. 2 is an exploded perspective view of a humidifier according to an example embodiment;

FIG. 3 is an exploded perspective view of a case assembly according to an example embodiment;

FIG. 4 is an exploded perspective view of a fan motor assembly according to an example embodiment;

FIG. 5 is an exploded perspective view of a base according to an example embodiment;

FIG. 6 is an exploded perspective view of a disk assembly according to an example embodiment;

FIG. 7 is a cross-sectional view of a disk assembly according to an example embodiment;

FIG. 8 is a block diagram illustrating a process of controlling a humidifier according to an example embodiment; and

FIG. 9 is a cross-sectional view of a humidifier according to an example embodiment.

DETAILED DESCRIPTION

Reference may now be made in detail to arrangements and embodiments, examples of which are illustrated in the accompanying drawings.

In the following detailed description, reference may be made to the accompanying drawings that form a part hereof,

2

and in which is shown by way of illustration specific preferred embodiments. These embodiments are described in sufficient detail to enable those skilled in the art to practice embodiments, and it is understood that other embodiments may be utilized and that logical structural, mechanical, electrical, and chemical changes may be made without departing from the spirit or scope of the embodiment. To avoid detail not necessary to enable those skilled in the art to practice the embodiment, the description may 5 omit certain information known to those skilled in the art. The following detailed description is, therefore, not to be taken in a limiting sense.

FIG. 1 is a perspective view of a humidifier according to an example embodiment. FIG. 2 is an exploded perspective 10 view of a humidifier according to an example embodiment. Other embodiments and configurations may also be provided.

Referring to FIGS. 1 and 2, a humidifier 1 may include a main body and a base 12 on which the main body is seated. 15 The main body may include a housing 10 defining an exterior thereof. The base 12 may have a first suction part through which air is suctioned.

The main body may include a tray 14 in which water is 20 stored, a case assembly 16 for guiding a flow of air within the housing 10, a fan motor assembly 20 for blowing the air, a control unit 22 for controlling operation of the humidifier 1, an input panel 28 seated on an upper portion of the fan motor assembly 20 to receive a manipulation command of the humidifier 1, and a disk assembly 30 seated on the tray 14. The disk assembly may humidify the air suctioned 25 through a first suction part (of the base).

The main body may also include a deco member 24 coupled to an upper portion of the housing 10.

The main body may include a discharge part 105 through 30 which humidified air is discharged.

The discharge part 105 may have a closed loop shape when viewed from a top surface of the main body. For example, the discharge part 105 may have a circular ring shape. Other shapes may also be provided.

The housing 10 may have an opened upper portion and an 35 opened lower portion. The housing 10 may include an upper opening and a lower opening.

The housing 10 may include a suction grill 102 having a second suction part through which air is introduced. The suction grill 102 may be separably coupled to the housing 10.

The upper opening of the housing 10 may provide a 40 passage through which the humidified air passes.

A seat end 101 on which the fan motor assembly 20 is 45 disposed on an upper portion of an inner circumferential surface of the housing 10.

An inner structure of the humidifier 1 may be described in 50 more detail.

FIG. 3 is an exploded perspective view of a case assembly 55 according to an example embodiment. Other embodiments and configurations may also be provided.

Referring to FIG. 3, the case assembly 16 may include an upper case 161 that serves as a fan housing, a middle case 165 disposed under the upper case 161 to guide the humidified air to the upper case 161, and a lower case 170 disposed under the middle case 165 and seated on the base 12.

The upper case 161 and the middle case 165 may be 60 integrated together (i.e., with each other). The lower case 170 may be separably coupled to the middle case 165. For example, the upper case 161 and the middle case 165 may be separably coupled to each other, and the middle case 165 and the lower case 170 may be integrated together (i.e., with

each other). Alternatively, the upper case 161, the middle case 165, and the lower case 170 may be integrated together (i.e., with each other) or may be separately provided and then coupled to each other.

A coupling part 162 may horizontally extend from an upper end of the upper case 161, and a coupling hole 163 may be defined in the coupling part 162. The coupling part 162 may be coupled to the fan motor assembly 20.

The coupling part 162 may be seated on and supported by the seat end 101 (of the housing 10) in a state where the coupling part 162 is accommodated into the housing 10.

The control unit 22 may be disposed on the middle case 165. The disk motor assembly 190 may be disposed on the middle case 165.

The disk motor assembly 190 may include a disk motor 192 generating power for rotating the disk assembly 30, a motor bracket 193 disposed on the disk motor 192, and a transmission part 195 connected to the disk motor 192 to transmit the power of the disk motor 192 to the disk assembly 30.

A buffer member 194 may be coupled to the motor bracket 193. A protrusion 169 inserted into the buffer member 194 may be disposed on the middle case 165.

Since the buffer member 194 coupled to the motor bracket 193 is coupled to the middle case 165, vibration generated while the disk motor 192 operates may be absorbed by the buffer member 194 to minimize transmission of vibration to the middle case 165.

The transmission part 195 may include at least one gear, for example. An opening 166 through which the transmission part 195 passes may be defined at the middle case 165. When the disk motor assembly 190 is disposed on the middle case 165, the transmission part 195 may pass through the opening 166 and may then be disposed in the middle case 165.

An insertion hole 167 in which an insertion part 172 of the lower case 170 is inserted may be defined under the middle case 165.

An air guide 176 for guiding the air suctioned through the second suction part 103 may be coupled to the middle case 165. A hole in which a portion of the air guide 176 is inserted may be defined in a side surface of the middle case 165. Thus, air suctioned through the second suction part 103 may pass through the hole by the air guide 176 and may then be introduced into the middle case 165.

A filter assembly 180 may be disposed on the case assembly 16. The filter assembly 180 may be coupled to the middle case 165 within the case assembly 16, for example.

The filter assembly 180 may include a filter frame 181 on which a filter 184 is seated, and a filter case 185 coupled to the filter frame 181.

At least one hook 182 coupled to the filter case 185 may be disposed on the filter frame 181. At least one coupling boss 186 coupled to the middle case 165 may be disposed on the filter case 185.

FIG. 4 is an exploded perspective view of a fan motor assembly according to an example embodiment. Other embodiments and configurations may also be provided.

Referring to FIG. 4, the fan motor assembly 20 may include a fan motor 210, a motor support 201 on which the fan motor 210 is seated, a fan 219 coupled to a shaft 212 of the fan motor 210, a motor pressing part 214 coupled to the motor support 201 to press the fan motor 210 and thereby prevent the fan motor 210 from vibrating, a guide 217 seated on the motor pressing part 214 and coupled to the motor support 201, and a cover 218 seated on an upper portion of the guide 217.

The fan 219 may be at a downstream side of the filter assembly 180.

A motor accommodation part 202 in which the fan motor 210 is accommodated may be disposed in the motor support 201. The motor support 201 may include one or more holes 203 through which the humidified air passes.

The shaft 212 (of the fan motor 210) may pass through the motor accommodation part 202 in a state where the shaft 212 (of the fan motor 210) is accommodated in the motor accommodation part 202. Thus, the fan 219 may be coupled to the shaft 212 of the fan motor 210 from a lower side of the motor support 201.

The motor support 210 may further include a seat groove 204 on which the motor pressing part 214 is seated, a first coupling hole 206 to which a coupling member coupled to the upper case 161 is coupled, and a second coupling hole 207 to which a coupling member coupled to the guide 217 is coupled.

A first accommodation part 216, in which a portion of the fan motor 210 is accommodated, may be disposed in the motor pressing part 214.

A second accommodation part 217A, in which the first accommodation part 216 of the motor pressing part 214 is accommodated, may be disposed in the guide 217. A coupling hole 217B, to which a coupling member coupled to the motor support 210 is coupled, may be defined in the guide 217.

FIG. 5 is an exploded perspective view of a base according to an example embodiment. Other embodiments and configurations may also be provided.

Referring to FIG. 5, the base 12 may include a lower base 122 and an upper base 126 seated on the lower base 122.

The base 12 may further include first suction parts 124 and 128 through which air is suctioned. The first suction parts 124 and 128 may include a first hole 124 defined in the lower base 122, and a second hole 128 defined in the upper base 126.

A tray accommodation part 127, in which a portion of the tray 14 is accommodated, may be disposed in the upper base 126.

Although the base 12 is constituted by two members, embodiments are not limited thereto. For example, the base 12 may be provided as a single member.

FIG. 6 is an exploded perspective view of a disk assembly according to an example embodiment. FIG. 7 is a cross-sectional view of a disk assembly according to an example embodiment. Other embodiments and configurations may also be provided.

Referring to FIGS. 2, 6, and 7, the disk assembly 30 may include a plurality of stacked disks 310, a shaft 320 passing through the plurality of disks 310 at a same time, a first disk cover 322 coupled to a first side of the shaft 320 at a first side of the plurality of disks 310, a second disk cover 324 coupled to a second side of the shaft 320 at a second side of the plurality of disks 310, and a handle 330 coupled to the first and second disk covers 322 and 324.

Each of the plurality of disks 310 may have a circular plate shape, for example, and may have a shaft hole 312 through which the shaft 320 passes.

The shaft 320 may have a non-circular cross-section, for example. The shaft hole 312 may have the same cross-sectional shape as the shaft 320. Thus, the plurality of disks 310 may rotate together with the shaft 320 by rotation of the shaft 320. The first suction parts 124, 128 may be disposed lower than the shaft 320 for rotating the disk assembly 30.

The second disk cover 324 may include a shaft coupling part 326 to which the other end of the shaft 320 is coupled.

An insertion groove 327, in which the shaft 320 is inserted, may be defined in the shaft coupling part 326. A screw thread may be formed on an end of the shaft 320, and a screw thread coupled to the screw thread of the shaft 320 may be formed on an inner circumferential surface of the insertion groove 327.

Accordingly, since the second disk cover 324 and the shaft 320 are screw-coupled to each other, when the second disk cover 324 rotates, the shaft 320 may rotate together with the second disk cover 324.

A handle coupling part 328 coupled to the handle 330 may be disposed on the second disk cover 324. The handle coupling part 328 may include a plurality of hooks spaced apart from each other.

A plurality of gear teeth 325, connected to the transmission part 195 (of the disk motor assembly 190), may be disposed on a circumference of the second disk cover 324.

The first disk cover 322 includes a shaft coupling part and a handle coupling part that have a same structure as the shaft coupling part 326 and the handle coupling part 329, which are disposed on the second disk cover 324. A detailed description with respect to structure of the first disk cover 322 may be omitted.

The handle 330 may include a handle body 332 to be grasped by a user, and a pair of cover coupling parts 334 and 337 disposed on both ends of the handle body 332. For example, the handle body 332 may include a first body 332A and a pair of second bodies 332B and 332C that extend from both ends of the first body 332A. The cover coupling parts 334 and 337 may be disposed on the pair of second bodies 332B and 332C, respectively. That is, the handle body 332 may have a "U" shape, for example.

A coupling hole 335, to which the handle coupling part 328 of each of the disk covers 322 and 324 is coupled, may be defined in each of the cover coupling parts 334 and 337. Since the handle coupling part 328 includes a plurality of hooks, the plurality of hooks may be elastically deformed in directions close to each other while passing through the coupling hole 335. Each of the plurality of hooks may be deformed to return to its original state after passing through the coupling hole 335. Thus, the handle coupling part 328 may be coupled to the cover coupling parts 334 and 337. The handle 330 may relatively rotate with respect to the disk covers 322 and 324 in a state where the handle 330 is coupled to each of the disk covers 322 and 324.

Each of the cover coupling parts 334 and 337 (of the disk assembly 30) may be seated on and supported by the tray 14. A guide protrusion 336 may be disposed on each of the cover coupling parts 334 and 337 such that the handle 330 is seated on the tray 14 in a state where the handle 330 rotates in one direction. The guide protrusion 336 may protrude from each of the cover coupling parts 334 and 337 in a direction that is inclined with respect to an extension direction of the second bodies 332B and 332C. That is, an angle between the guide protrusion 336 and the second bodies 332B and 332C may be greater or less than an angle of approximately 180°.

The tray 14 may include a first seat groove 142 on which each of the cover coupling parts 334 and 337 is seated and a second seat groove 143 on which the guide protrusion 336 is completely seated in only a state where the handle 330 rotates in one direction.

When the disk motor 192 operates in a state where the disk assembly 30 is seated on the tray 14, a power of the disk motor 192 may be transmitted to the second disk cover 324 through the transmission part 195. As a result, the second disk cover 324 may rotate in one direction, and thus, the shaft 320, the plurality of disks 310, and the first disk cover

322 may rotate in one direction together with the second disk cover 324. The handle 330 may be maintained in the stopped state without rotating in the state where the handle 330 is seated on the seat grooves 142 and 143.

5 The handle 330 may relatively rotate with respect to the shaft 320 in a state where the handle 330 is seated on the tray 14 without the shaft 320 being directly seated on the tray 14. Thus, damage of the tray 14 while the shaft 320 rotates may be prevented. Additionally, since the handle coupling part 10 328 rotates within a range of the coupling hole 336 of the handle 330, rotation noises may be reduced.

15 FIG. 8 is a block diagram illustrating a process of controlling a humidifier according to an example embodiment. Other embodiments and configurations may also be provided.

Referring to FIG. 8, the humidifier 1 may include a water level detection unit 51 for detecting a water level, a control unit 50 for controlling the fan motor 210 and the disk motor 20, an input unit 282 for receiving an operation command, and a light emitting unit 29 for emitting light.

The water level detection unit 51 may detect a water level within the tray 14 based on capacitance.

25 The input unit 282 may be disposed on the input panel 28. For example, the input unit 282 may receive a command by a user's touch manipulation. The light emitting unit 29 may be disposed on the input panel 28.

30 The control unit 50 may control the fan motor 210 and the disk motor 192 based on information of the water level detected by the water level detection unit 51.

The control unit 50 may control the fan motor 210, the disk motor 192, and the light emitting unit 29 according to the command inputted to the input unit 282.

35 FIG. 9 is a cross-sectional view of a humidifier according to an example embodiment. Other embodiments and configurations may also be provided.

A process of assembling the humidifier may be described below with reference to FIGS. 1 to 9.

40 The tray 14 is seated on the base 12.

The disk assembly 30 is seated on the tray 14. As described above, the handle 330 may be seated on the tray 14 in the disk assembly 30. More particularly, the handle 330 may be seated on the tray 14 only in a state where the handle 330 rotates in one direction.

45 When the disk assembly 30 is seated on the tray 14, the plurality of disks 310 may be spaced apart from a bottom surface of the tray 14. A portion of the plurality of disks 310 may protrude to outside of the tray 14.

50 The case assembly 16 may be seated on the base 12.

When the case assembly 16 is seated on the base 12, the lower case 170 may cover the tray 14, and the middle case 165 may cover the plurality of disks 310 that protrude to outside of the tray 14. A lower end of the air guide 176 coupled to the middle case 165 may be disposed adjacent to the plurality of disks 310. The lower end of the air guide 176 may be disposed higher than the shaft 320 (of the disk assembly 30).

55 When the case assembly 16 is seated on the base 12, the transmission part 195 (of the disk motor assembly 190) may be engaged with the second disk cover 324 (of the disk assembly 30).

60 When the case assembly 16 is seated on the base 12, a portion of the middle base 164 may be seated on the tray 14.

65 When the case assembly 16 is seated on the base 12, the filter assembly 180 may be disposed above the disk assembly 30.

The control unit 22 may be coupled to the case assembly 16. The case assembly 16 may be seated on the base 12 in a state where the control unit 22 is coupled to the case assembly 16.

The housing 10 is seated on the base 12.

The fan motor assembly 20 is accommodated into the housing 10 from an upper side of the housing 10, and then the fan motor assembly 20 is coupled to the housing 10 and the upper case assembly 16.

The seat end 101 (of the housing 10) is seated on the coupling part 162 (of the case assembly 16), and the fan motor assembly 20 is seated on the coupling part 162. The fan motor assembly 20 may be coupled to the seat end 101 and the coupling part 162 by a single coupling member.

The housing 10, the case assembly 16, and the fan motor assembly 20 may be separated from the base 12 as one module. That is, the main body may be separated from the base 12 as one module.

The deco member 24 may be coupled to an upper portion of an inner circumferential surface of the housing 10, and the input panel 28 may be coupled to an upper portion of the fan motor assembly 20 to complete assembly of the humidifier.

The fan motor assembly 20 may be coupled to the housing 10 after the input panel 28 is coupled to the fan motor assembly 20.

A process of separating the filter assembly 180 may now be described.

To clean the filter assembly 180 or the fan 219, the main body may be separated from the base 12.

Since the housing 10 is coupled to the case assembly 16 and the fan motor assembly 20, the case assembly 16, the fan motor assembly 20, and the housing 10 may be separated from the base 12 at a same time.

The filter assembly 180 may be disposed under the fan 219. The filter assembly 180 may be disposed between the fan 219 and the disk assembly 30. The filter assembly 180 may be disposed above the fan 219.

Thus, when the main body is separated from the base 12, the state in which the tray 14 is seated on the base 12 may be maintained. The state in which the disk assembly 30 is seated on the tray 14 may be maintained.

Thus, when the main body is separated from the base 12, the filter assembly 180 is exposed to the outside. A user may separate the filter assembly 180 from the case assembly 16 to clean the filter 184.

The filter assembly 180 may cover a lower side of the fan 219 in a state where the filter assembly 180 is mounted on the case assembly 16. An extension direction of the shaft 212 (of the fan motor 210) may cross the filter assembly 180. A portion or the whole of the fan 219 may be disposed to overlap the filter assembly 180 in a vertical direction or a direction in which the air flows.

When the filter assembly 180 is separated from the case assembly 16, the fan 219 is exposed. Thus, the user may clean the fan 219 that is exposed to the outside in a state where the filter assembly 180 is separated from the case assembly 16.

According to the embodiment, when the housing 10 is separated from the base 12, and the filter assembly 180 is separated from the case assembly 16, the fan 219 is exposed. Thus, since the user cleans the fan without separating the fan 219, a user's convenience may be improved.

A flow of air within the humidifier may now be described.

The first suction parts 124 and 128 defined in the base 12 may form a first suction passage P1. The tray 14 and the

lower case 170 of the case assembly 16 may be spaced apart from each other to form a portion of the first suction passage P1.

The suction grill 102 and the air guide 176 may be spaced 5 a predetermined distance from each other, and a second suction passage P2 may be defined between the suction grill 102 and the air guide 176. A suction filter 60 for filtering suctioned air may be disposed in the second suction passage P2. The suction filter 60 may filter the air suctioned through 10 the second suction part 103.

The fan 219 may rotate by operation of the fan motor 210, and the disk 310 may rotate by operation of the disk motor 192.

The disk 310 may rotate in a clockwise direction in FIG. 15 9, for example. When the disk 310 rotates, the disk 310 wetted by water may be exposed to outside of the tray 14.

When the fan 219 rotates, air may be suctioned into the 20 humidifier 1 through the first suction parts 124 and 128 and the second suction part 103. That is, the air may be suctioned by passing through the base 12, and also the air may be 25 suctioned by passing through the housing 10.

Since the suction filter 60 is disposed in the second 25 suction passage P2, the suction filter 60 may serve as air flow resistance in the suction passage P2.

Thus, in the humidifier 1, an amount of air suctioned 30 through the first suction parts 124 and 128 in the air introduced into the humidifier 1 may be greater than an amount of air suctioned through the second suction part 103. Therefore, the first suction parts 124 and 128 may be called "main suction parts", and the second suction part 103 may be called an "auxiliary suction part" or "additional suction part".

The first suction parts 124 and 128 may be disposed lower 35 than the shaft 320 of the disk assembly 30, and the second suction part 103 may be disposed higher than the shaft 320.

The air suctioned through the first suction parts 124 and 128 may flow upward along the first suction passage P1 to flow into a space between the wetted disks 310. Thus, the air 40 may contain moisture while contacting the disks 310.

The first suction parts 124, 128 may be defined in the base 12 to effectively prevent the air from being introduced into the humidifier 1 through the first suction part 124, 128, thereby preventing inside of the humidifier 1 from being 45 contaminated.

The air suctioned through the second suction part 103 may pass through the suction filter 60 to flow toward the disk assembly 30 by the air guide 176. The air suctioned through the second suction part 103 may contain moisture while flowing into the space between the wetted disks 310 to contact the disks 310.

The second suction part 103 may be defined in the suction grill 102 to primarily prevent foreign substances from being introduced by the suction grill 102. The suction filter 60 may be disposed inside the suction grill 102 to secondarily prevent foreign substances from being introduced by the suction filter 60. Thus, contamination of inside of the humidifier due to introduction of the foreign substance may be prevented.

Since the second suction part 103 is defined in a portion 55 of the housing 10, and a user is capable of seeing the first suction part 124, 128, the humidifier 1 may be improved in a sensor of beauty.

The humidified air may be filtered while passing through 60 the filter assembly 180. After the humidified air passes through the fan 219, the air may be guided by the upper case 161 of the case assembly 16 to flow upward.

The humidified air may pass through the one or more holes 203 of the fan motor assembly 20 and then be discharged from the humidifier 1 through the discharge part 105 defined between the deco member 24 and the guide 217.

As described above, since the discharge part 105 has the closed loop shape, the humidified air may be discharged in all directions (i.e., at approximately) 360°, and thus may be uniformly spread into the indoor space.

Since the deco member 24 and the guide 217 define the discharge part 105 to guide discharge of the air, the deco member 24 may also be called a first guide, and the guide 217 may also be called a second guide.

An operation of the light emitting unit 29 may now be described.

The input unit 282 may include a printed circuit board 284 on which the light emitting unit 29 is mounted. The light emitting unit 29 may pass through the cover 218 of the fan motor assembly 20 and may then be disposed within the guide 217. The light emitting unit 29 may include a plurality of light emitting diodes (LEDs) that emit light having various colors. The cover 218 (of the fan motor assembly 20) may be omitted. In this example, the input panel 28 may serve as the cover 218.

At least one humidification mode may be selected by the input unit 282. A lighting mode may be selected by the input unit 282.

When the lighting mode is selected, the control unit 50 may turn the light emitting unit 29 on in a state where the fan motor 210 and the disk motor 192 are stopped in operation. The light emitting unit 29 may emit light having a first color. Since the user is capable of selecting the lighting mode, the humidifier may serve as a lighting apparatus.

The control unit 50 may control the light emitting unit 29 such that the light emitting unit 29 emits light having a color different from the first color according to the selected humidification mode. The light emitting unit 29 may emit light having a single color. The control unit 50 may control the light emitting unit 29 such that the light emitting unit 29 emits light having different colors according to the humidification modes.

The light emitting unit 29 may emit light to the guide 217. The guide 217 may be formed of a transparent or translucent material such that the light emitted from the light emitting unit 29 passes through the guide 217.

The light emitting unit 29 may pass through the guide 217 to emit to the deco member 24. Thus, the light may be emitted through the deco member 24. The deco member 24 may be formed of a transparent or translucent material. The deco member 24 may serve as a reflection plate.

When the humidifier operates, light may be emitted from the light emitting unit 29. Thus, the user may easily recognize that the humidified air is discharging.

Although the light emitting unit 29 is disposed on the input unit 282 inside the guide 217, embodiments are not limited thereto. For example, the light emitting unit 29 may be disposed on the guide 217 or the deco member 24.

Although the deco member 24 is provided as a separate part and is then coupled to the housing 10, embodiments are not limited thereto. For example, the deco member 24 may be integrated with the housing 10.

Embodiments may provide a humidifier having an improved sense of beauty and may prevent the inside thereof from being contaminated.

A humidifier may include a main body having a discharge part; a base on which the main body is seated, the base having a suction part through which air is suctioned; a tray

seated on the base to store water; and a disk assembly seated on the tray to humidify the air suctioned through the suction part.

When the main body is seated (or provided) on the base, the main body may cover the tray, and the air suctioned through the suction part may flow upward from the inside of the main body along the outside of the tray.

The main body may include: a case assembly that covers the tray; and a housing that covers the case assembly, and the air suctioned through the suction part may flow between the case assembly and the tray.

The suction part may be disposed lower than a shaft for rotating the disk assembly.

The humidifier may further include: a filter assembly through which humidified air passes; and a fan disposed at a downstream side of the filter assembly.

The main body may further include an additional suction part for suctioning air.

The additional suction part may be disposed higher than the suction part of the base.

The additional suction part may be disposed higher than a shaft for rotating the disk assembly.

The main body may further include a suction filter to filter the air suctioned through the additional suction part.

The main body may further include an air guide to guide the air suctioned through the additional suction part toward the disk assembly.

The additional suction part may be disposed between the discharge part and the suction part of the base based on the height thereof.

In at least another embodiment, a humidifier may include a base having a suction part; a tray seated on the base; a disk assembly seated on the tray to humidify air suctioned through the suction part; and a case assembly seated on the base to cover the tray, wherein the air suctioned through the suction part flows between the case assembly and the tray.

The suction part may be disposed lower than a shaft for rotating the disk assembly.

The humidifier may further include a housing that covers the case assembly, and the housing may have an additional suction part.

The additional suction part may be disposed higher than the suction part of the base.

The additional suction part may be disposed higher than a shaft for rotating the disk assembly.

In at least another embodiment, a humidifier may include: a base having a first suction part; a main body seated on the base, the main body having a second suction part through which air is suctioned and a discharge part through which humidified air is discharged; a tray seated on the base to store water; and a disk assembly seated on the tray to humidify the air suctioned through the first and second suction parts.

The discharge part may be disposed above the first and second suction parts.

The first suction part may be disposed lower than a shaft for rotating the disk assembly, and the second suction part may be disposed higher than the shaft.

The main body may include a case assembly seated on the base to cover the tray, and the case assembly and the tray may define a first suction passage through which the air suctioned through the first suction part flows.

Any reference in this specification to "one embodiment," "an embodiment," "example embodiment," etc., means that a particular feature, structure, or characteristic described in connection with the embodiment is included in at least one embodiment of the invention. The appearances of such

11

phrases in various places in the specification are not necessarily all referring to the same embodiment. Further, when a particular feature, structure, or characteristic is described in connection with any embodiment, it is submitted that it is within the purview of one skilled in the art to effect such feature, structure, or characteristic in connection with other ones of the embodiments.

Although embodiments have been described with reference to a number of illustrative embodiments thereof, it should be understood that numerous other modifications and embodiments can be devised by those skilled in the art that will fall within the spirit and scope of the principles of this disclosure. More particularly, various variations and modifications are possible in the component parts and/or arrangements of the subject combination arrangement within the scope of the disclosure, the drawings and the appended claims. In addition to variations and modifications in the component parts and/or arrangements, alternative uses will also be apparent to those skilled in the art.

What is claimed is:

1. A humidifier comprising:

a base having a first suction part through which air is suctioned;
a main body having a discharge part, the main body provided on the base;
a tray on the base to store water; and
a disk assembly on the tray to humidify the air suctioned through the first suction part,
wherein the main body includes:
a second suction part for suctioning air, and
an air guide to guide the air suctioned through the second suction part toward the disk assembly.

2. The humidifier according to claim 1, wherein the main body covers the tray when the main body is on the base, and the air suctioned through the first suction part flows upward from inside of the main body along or outside of the tray.

3. The humidifier according to claim 2, wherein the main body includes:
a case assembly to cover the tray; and
a housing to cover the case assembly, and
the air suctioned through the first suction part flows between the case assembly and the tray.

4. The humidifier according to claim 1, wherein the first suction part is disposed lower than a shaft for rotating the disk assembly.

5. The humidifier according to claim 1, further comprising:

a filter assembly to pass humidified air; and
a fan at a downstream side of the filter assembly.

6. The humidifier according to claim 1, wherein the second suction part is disposed higher than the first suction part of the base.

7. The humidifier according to claim 6, wherein the second suction part is disposed higher than a shaft for rotating the disk assembly.

12

8. The humidifier according to claim 1, wherein the main body further includes a suction filter to filter the air suctioned through the second suction part.

9. The humidifier according to claim 1, wherein the second suction part is between the discharge part and the first suction part of the base based on height of the second suction part.

10. A humidifier comprising:
a base having a first suction part;
a tray on the base;
a disk assembly on the tray to humidify air suctioned through the first suction part; and
a case assembly, on the base, to cover the tray,
wherein the air suctioned through the first suction part flows upward between the case assembly and the tray,
and
the first suction part is disposed lower than the case assembly.

20 11. The humidifier according to claim 10, wherein the first suction part is disposed lower than a shaft for rotating the disk assembly.

12. The humidifier according to claim 10, further comprising a housing to cover the case assembly, the housing having a second suction part.

13. The humidifier according to claim 12, wherein the second suction part is disposed higher than the first suction part of the base.

14. The humidifier according to claim 12, wherein the second suction part is disposed higher than a shaft for rotating the disk assembly.

30 15. A humidifier comprising:
a base having a first suction part;
a main body on the base, the main body having a second suction part through which air is suctioned and a discharge part through which humidified air is discharged;
a tray, on the base, to store water; and
a disk assembly, on the tray, to humidify the air suctioned through the first suction part and the second suction part.

16. The humidifier according to claim 15, wherein the discharge part is disposed above the first and second suction parts.

45 17. The humidifier according to claim 15, wherein the first suction part is disposed lower than a shaft for rotating the disk assembly, and
the second suction part is disposed higher than the shaft for rotating the disk assembly.

18. The humidifier according to claim 15, wherein the main body includes a case assembly, on the base, to cover the tray, and the case assembly and the tray define a first suction passage through which the air suctioned through the first suction part flows.
